UNITED STATES PATENT OFFICE

2,331,560

REFRIGERATOR

Pietro Maniscalco, Chicago, Ill.

Application November 15, 1940, Serial No. 365,766

10 Claims.

(Cl. 62—89)

This invention relates to improvements in refrigerators.

One of the main objects of this invention is to provide an improved refrigerator which comprises not only an improved food storing chamber and ice cube making chamber, but which furthermore comprises a highly efficient and desirable freezing chamber for promptly freezing and conserving meats and other foods, etc., without causing any shrinkage or loss of weight thereof.

Another object of this invention is to provide the refrigerator with an improved freezing chamber for preserving frozen food therein, and wherein said chamber is arranged and mounted in the cabinet so that a small space is formed between it and the cabinet wall to provide an ice cube freezing chamber, and a larger space is likewise formed to provide a chamber for storing food and the like.

Another object of this invention is to provide such freezing chamber comprising a jacket arranged to contain liquid in its wall and having refrigerant conducting means mounted in said liquid for chilling the same, thereby tending to maintain a more uniform cooling effect in the refrigerator and a more extended effect after the compressor-condenser unit is at rest.

Another object of this invention is to provide vent-regulated partition means in the food storage space, so as to produce several individual chambers provided with means for controlling the circulation of cool air from one chamber to another, in order to be able to adjust and vary the temperature in either of these chambers and thus selectively vary the refrigerating effect of this device on the different objects stored in the different chambers; and likewise be able to close off some of said chambers and thus also economize on the use of refrigerant.

Another object of this invention is to arrange and construct my improved freezing device so that it can be built into a newly constructed cabinet; and it can furthermore be installed detachably in the cabinet of a refrigerator, taking the place of the usual ice cube freezing unit therein, and can be operatively connected with the customary compressor-condenser unit of such refrigerator.

These and various other objects and advantages are attained with this invention, as will become apparent from the following description, taken in connection with the accompanying drawings wherein the invention is disclosed in its preferred form, it being apparent that various

other arrangements and forms of construction may be adopted in carrying out the objects and purposes of this invention.

In the drawings:

5 Fig. 1 is an elevational view illustrating a refrigerator embodying this invention in its preferred form, parts being broken away.

Fig. 2 is an enlarged view of an apertured door including circulation-controlling means on one 10 of the storage chambers.

Fig. 3 is a horizontal sectional view of this invention taken on line 3—3 of Fig. 1.

Fig. 4 is an enlarged vertical sectional view, taken on line 4—4 of Fig. 3, the top and bottom 15 parts being omitted.

Fig. 5 is an enlarged vertical sectional view, taken on line 5—5 of Fig. 1.

Fig. 6 is a perspective view of the freezing device, which is removably mountable in the cabinet of a domestic refrigerator or the like.

20 This invention is illustrated in the drawings in its preferred form of construction, and as being embodied in a domestic type of refrigerator comprising a cabinet 10, said cabinet being shown as provided with upstanding walls 11 having a top wall 12 and a bottom wall 13 thereon and a door 14 hinged thereto, all provided with suitable heat insulating material, as indicated.

30 A refrigerator of this type is usually provided with a compressor-condenser unit or operating unit 15, which is illustrated as including a compressor 16, a driving motor 17, a condenser 18 and a tank 19; and these are provided with suitable conduits connecting the same, including the feed conduit 20 extending from the tank and having an expansion valve 21 therein, and the return conduit 22 for returning the refrigerant to the compressor 16. Said unit 15 is mounted 35 in a machinery chamber 23, which is herein provided at the top of the cabinet.

The essential feature of this invention comprises a novel freezing device 25, which is shown per se in Fig. 6, and is shown otherwise as installed in the cabinet 10. It is preferably provided with supporting legs 26 which are hinged thereto, so that they may be swung inwardly thereunder, as indicated by dotted lines in Fig. 4. This device is thereby adapted for convenient 45 installation in and removal from any suitable cabinet; and it can thus be readily built into a new cabinet, and can also be installed in the cabinets of existing refrigerators, and have its refrigerant conducting conduits operatively connected with a suitable operating unit. When

50 55

this device is installed in such a former type of cabinet it takes the place of the customary ice-making unit therein and is substituted in place thereof.

This device 25 is constructed in the form of a jacket having a space or chamber means in its wall adapted to receive a liquid therein, and in this illustrated form the jacket includes hollow walls providing a liquid chamber 27 therebetween, and also providing a freezing chamber 28 within the inner walls, having a door 29 hinged thereon and adapted to close said chamber 28 air-tight. Refrigerant conducting means 30 is provided on said jacket, and is shown as a continuous coil wound around the inner walls and immersed in said liquid. Said coil is connected by coupling means 31 with the expansion valve 21 and by coupling means 32 with the return pipe 22.

The liquid used therein is preferably a frost resisting one, such as a strong salt brine, a diluted solution of diethylene-glycol, or the like, which can be chilled to exert extreme cooling and freezing effect on the inner chamber 28 without becoming congealed or solid in the liquid chamber 27.

The freezing device 25 extends substantially as a partition across the upper part of the cabinet, adjacent the top 12, thereby providing a small chamber 33 between the top of the device 25 and the top wall 12 of the cabinet, and a door 34 is hinged at the front thereof. This chamber 33 provides the ice-making chamber, adapted to have suitable pans 35 placed therein for making ice cubes. With this arrangement the space between the lower side of the device and the lower part of the cabinet also provides a storage space 36 for food and the like.

Novel shelves 37 are provided in this cabinet, which are substantially in the form of partition walls extending across the cabinet, and are shown mounted removably on bracket means 38 provided on legs 26. Each partition is preferably in the form of a perforated plate having elongated slots 39 therein, as best shown in Fig. 3; and control means is provided thereon, which is shown as including a slide plate 40 adjustably slidable on partition plate 37 and provided with slots 41 therein, adapted to register with slots 39 for circulation of air therethru, and likewise to be closed when desired. Doors 43 are placed in front of partitions 37, being hinged on a leg 26, by means 44 and 45 on said leg and doors, so as to provide several separate or individual chambers 46, 46' and 46'' within the storage space 36 in the cabinet. With this arrangement the separate storage chambers 46, 46' and 46'' can be retained at different temperatures, by moving the hooks 47 which depend from plates 40 and sliding said plates. Likewise, the doors 43 are provided with slots 49 and have each a control plate 50 slidable thereon containing slots 51, adapted to register with slots 49, so that the ventilation through the doors can be adjusted or closed off by moving knobs 53 which extend forwardly from said doors, and sliding said plates.

A drip pan 54 is preferably also mounted under the freezing device 25, adapted to collect any moisture caused by defrosting of the freezing device, etc., and this pan is furthermore well adapted for receiving fish and the like to be chilled or frozen therein.

It is apparent from the above disclosure that with this invention I have provided a novel form of freezing device for a refrigerator, which is

especially adapted for quickly freezing various types of foods therein, and for preserving them in a frozen condition for an extended length of time. It is furthermore apparent that I have herewith provided such a freezing device which can be built into newly constructed cabinets, and can likewise be installed in the existing cabinets of domestic refrigerators. It is moreover apparent that by this arrangement of the device in the cabinet I also provide a small ice-making chamber 33 therein, and a plurality of separate and independent food storage chambers 46, 46' and 46'', and that these chambers can be controlled so as to retain them at different temperatures, and one or more of them can be shut off from the circulation of cool air, when not required, and thereby also effect economy in the operation of the compressor-condenser unit.

I claim:

1. A refrigerator comprising a cabinet having heat insulated walls, chamber forming means mounted in the cabinet and having refrigerant conducting means thereon to provide a freezing chamber, partition means mounted apart across the cabinet providing shelves therein and having doors thereon, thereby forming several individual storage chambers, and apertured means provided on at least one of the partition means and doors for controlling circulation of air therethru.

2. The subject matter set forth in claim 1, wherein each of said partition means comprises an apertured plate and the doors are apertured, all provided with control means thereon for adjusting the aperture openings and to close the same, whereby the circulation of cool air can be controlled and also closed off from some of said chambers.

3. In a refrigerator containing a cabinet having heat insulated walls and an operating unit associated therewith, a freezing device in the cabinet consisting of a double-walled jacket providing a freezing chamber therein and having a liquid containing space in its double wall, and refrigerant conducting means immersed in the liquid and actuated by said operating unit for chilling said liquid and producing a uniform freezing effect thereby in said chamber, said jacket extending across the interior of the cabinet to cooperate with the cabinet walls and divide said interior into an ice making space and a food storage space on the opposite sides of the jacket.

4. A refrigerating device adapted for convenient installation in a refrigerator having a cabinet with heat insulated walls and an operating unit associated therewith, said device comprising a jacket having supporting members attached thereto whereby to support the jacket removably in the cabinet to extend across the interior thereof and divide said interior into two separate cooling chambers, said jacket providing a food-freezing chamber in its interior and having a space in its walls surrounding said chamber for containing liquid, refrigerant conducting means immersed in the liquid in said space and adapted to be operably connected with said operating unit, and a door on said jacket to close the chamber for preserving frozen food therein.

5. The subject matter set forth in claim 4, wherein the jacket supporting members are in the form of movably mounted legs, adapted to support the device in a cabinet, and shelf means are detachably supported on bracket means provided on said legs, said shelf means being detachable from the bracket means and the device being readily removable from the cabinet.

6. In a domestic type of refrigerator containing a cabinet having heat insulated walls and an operating unit associated therewith, a freezing device comprising a door-equipped jacket mounted across the cabinet, providing a chamber therein for freezing and conserving foods and having a liquid containing space in its walls, refrigerant conducting means immersed in said liquid and being detachably and operably connected with said operating unit, thereby providing a small ice-making chamber between the device and the top of the cabinet, legs movably mounted under the device to support it in the cabinet and being removable with the device from the cabinet, and shelf plate means extending across the cabinet providing partitions therein, being removably supported on said legs and having doors in front thereof, thereby providing individual chambers for storing foods therein, said device with legs and doors and partition means being all readily removable from the cabinet and readily mountable therein.

7. The subject matter set forth in claim 6, wherein the partitions and the doors are provided with adjustable ventilating means operable for controlling the circulation of cool air thru and thereby the temperature in these several storage chambers, and also for closing off some of the chambers, while others are in use.

8. In a domestic type of refrigerator containing a cabinet having heat insulated walls, a freezing device comprising refrigerant conducting means thereon and a door-equipped freezing chamber therein for freezing foods, supporting members under said device whereon it is supported in the cabinet to be readily removable therefrom and to extend across its interior at the upper part of the cabinet thereby providing a space above it to serve as an ice-making chamber, also providing chamber means below it to serve for storing foods and the like, and a drip pan removably mounted on said members directly beneath said device,

adapted for chilling and freezing fish and also for receiving any moisture that may descend from the device.

9. A domestic type of refrigerator comprising 5 a cabinet containing heat insulated walls and having an operating unit associated therewith, a freezing device including a jacket constructed to provide a freezing chamber for freezing foods therein and extending across the interior of the 10 cabinet near one of said walls to cooperate therewith for dividing said interior into a relatively small space for making ice cubes therein and into a larger space for storing foods, said jacket containing a freezing unit actuated by said operating unit, means on the jacket for supporting 15 it in the cabinet to provide for ready insertion therein and removal therefrom, and detachable partition means and door means provided for the storage space to produce several individual 20 closed chambers for storing foods therein.

10. A domestic type of refrigerator comprising a cabinet having heat insulated walls providing a large interior space therein and having an operating unit associated therewith, a freezing 25 device comprising a door-equipped closed casing constructed to provide a freezing chamber therein and containing a freezing unit detachably connected with said operating unit, said device being removably mounted across the cabinet's interior 30 to cooperate therewith for dividing it into a relatively small ice freezing space and a larger and less cold space for storing foods, means for removably supporting said casing in said interior, and shelf means in said larger space being associated with said supporting means and providing 35 several food storing chambers, the construction being adapted for readily removing said casing with its freezing unit and also said shelf means readily from the cabinet and likewise readily inserting the same therein.

PIETRO MANISCALCO.
